UNITED STATES PATENT OFFICE.

BENJAMIN ADRIANCE AND AMOS CALLESON, OF BROOKLYN, NEW YORK; SAID CALLESON ASSIGNOR TO SAID ADRIANCE.

METHOD OF SEALING BOTTLES.

965,498.

Specification of Letters Patent. Patented July 26, 1910.

Original application filed August 11, 1908, Serial No. 447,968. Divided and this application filed February 20, 1909. Serial No. 479,032.

To all whom it may concern:

Be it known that we, BENJAMIN ADRIANCE and Amos CALLESON, citizens of the United States, residing in Brooklyn, borough of Brooklyn, New York, have invented certain new and useful Improvements in the Method of Sealing Bottles; and we do hereby declare the following to be a full, clear, and exact description of the invention, such 10 as will enable others skilled in the art to which it appertains to make and use the same, reference being had to the accompanying drawings, and to characters of reference marked thereon, which form a part of this 15 specification.

This invention relates to the sealing of bottles by means of flanged caps, and it consists in certain improvements in the method utilized in this art which distinguish from 20 prior expedients in the following principal ways:

In the improved sealing head herein shown and described, the contraction of the lower or edge part of the cap-flange, whereby to 25 bend it under and into locking engagement with the shoulder on the bottle, is accomplished by an annular series of jaws each in the form of a bell-crank lever having one arm projecting downwardly and the other 30 inwardly; upon pressure being exerted upwardly against the inwardly projecting arms of the jaws, the latter move on their fulcrums with the effect of contracting the annulus formed by their downwardly projecting arms so that the latter turn or bend 35 the flange of the cap in under the shoulder on the bottle. The cavity produced by the jaws being initially approximated to the initial diameter of the cap and each jaw having 40 its axis of movement or fulcrum relatively near its acting or bending face or edge, it requires but slight movement of the jaws to effect the interlocking of the cap to the bottle head, and, in addition, the edge part is 45 by a drawing, as well as by a bending, action forced under the shoulder on the bottle-head, whereby a more substantial grip of the cap on the head is obtained than by mere bending, and the danger of crushing the head is 50 reduced. The improved sealing-head is further so constructed that, in the applying of caps having corrugated flanges, commonly known as "Crowns," its cap-bending portions impinge on the inner corrugations of

the cap-flange; so far as we are aware, the 55 method of sealing bottles thus involved in the use of our improved sealing head is new and it entails the following advantage, to wit, the uniform inward displacement of the edge part of the cap and a consequent even 60 distribution of pressure of the cap flange on the bottle shoulder, annularly thereof, which results are not in practice possible in the method previously employed where, the bending portions being intended to operate 65 upon all the outer corrugations of the cap, they almost invariably only impinge against a part of them; it entails the further advantage that the bending portions or tool being operative directly upon the inner corruga- 70 tions, the bending of the cap into locking engagement with the bottle-shoulder is accentuated and a more secure grip attained than where the tool operates indirectly, through the medium of the outer corruga- 75 tions.

The invention will be found fully illustrated in the accompanying drawings, in which,

Figure 1 shows in side elevation, partly in section, a bottle sealing or closing machine provided with our improved sealing-head; Fig. 2 is a vertical central sectional view of the improved sealing-head and of a cap, the head of a bottle about to be closed by the 85 cap and certain parts of the sealing-head appearing in elevation, and the bottle, cap and the parts of the sealing-head being shown in their first position; Fig. 3 is a view substantially similar to Fig. 2, except that a 90 part of the bottle-head appears in section, the parts being in their second position; Fig. 4 is a view similar to Fig. 3, the parts being in their third position; Fig. 5 is a vertical sectional view of the closed bottle-head; Fig. 95 6 is an underneath plan view of the sealing-head; and, Fig. 7 and Fig. 8 illustrate details of the sealing-head, Fig. 7 being a vertical sectional view and Fig. 8 an elevation.

In Fig. 1 is shown a bottle-sealing or closing machine *a* provided with the improved sealing-head *b* and with suitable means *c* for raising a bottle *A* and causing its mouth to impinge against the cork lining *e* of a cap *f*, having a corrugated flange, and thereupon 100 forcing the cap upwardly against means in the sealing-head whose first operation is to 105 produce a sealing or closing contact between

the mouth of the bottle and the lining of the cap and whose second operation is to secure the cap to the bottle-head by interlocking the cap-flange with the shoulder on the bottle-head.

The improved sealing-head comprises a hollow stem *g* having internal threading *h* at its upper end and an exterior threaded flange *i* at its lower end; a plug *j* being 10 screwed into its upper end and a cylindrical socket *k* being screwed onto its lower end and having an internal shoulder *l* at the bottom thereof. The socket receives a ring *m* having an external shoulder *n* which abuts 15 against the shoulder *l*, and it also receives a ring *o* which has an external flange *o'* projecting between the ring *m* and the flange *i* of the stem *g*. The ring *o* snugly fits the ring *m* and has the radial slits *p* coinciding 20 with the semi-circular radial recesses *q* in the ring *m*, one recess for each jaw (Fig. 6). To facilitate the assembling of the parts, the ring *m* is preferably split diametrically (Fig. 6).

25 In the slits *p* and the recesses *q* are arranged the jaws *r*. Each jaw is substantially a lever provided with an inwardly projecting arm *s* and with a bearing-portion *t* of substantially semi-circular form, 30 such bearing-portion being of the same radius as that of the recesses *q*. Each jaw has a shoulder *u* which abuts against a shoulder *v* on the ring *m* below its recesses, such shoulders co-operating to limit the retracting 35 movement of the jaws. The jaws are normally held retracted, their shoulders *u* being in contact with the shoulder *v* of ring *m*, by a follower *w* which bears down upon their arms *s* and is under the pressure of a 40 spiral spring *x* arranged in the stem *g* and interposed between said follower and the plug *j*; the tension of the spring may be adjusted by manipulating the plug *j*. The follower moves vertically in ring *o*.

45 On referring to Fig. 6 it will be seen that the acting portions *y* of the jaws *r* are spaced from each other at intervals corresponding with the spaces between the inner corrugations of the cap *f*; further, that such acting 50 portions are rounded, and that the diameter of the circle represented by the acting portions *y* of the jaws in their rest position approximates the diameter of the inner corrugations of the cap, or is at least less than 55 the diameter of the outer corrugations of the cap. Thus, when a cap of the crown type is thrust into the cavity formed by the annular series of jaws, the cap is compelled to occupy such a relation to the jaws that 60 the acting portions *y* of the latter enter between its outer corrugations and are directly opposed to its inner corrugations.

The operation is substantially as follows: 65 A cap being arranged above the bottle *A*, and being held by any suitable means, such

as *z* in Fig. 2, the mechanism *c* is caused to raise the bottle *A* so that it first impinges against the lining of the cap and then forces the cap up into the cavity formed by the jaws *r*, the cap adjusting itself rotatively 70 on its own axis so that its outer corrugations enter between the acting portions *y* of the jaws *r*. Upon the upward movement of the bottle and cap being continued, the cap impinges against the arms *s* of the jaws, and, 75 the tension of spring *x* being overcome, the jaws turn in their bearings, formed by the recesses *q*, and thereby have their acting portions moved into a more contracted relation. During this part of the action and 80 up to the time that the bottle and cap cease their upward movement, the jaws not only act to bend the flange-edge under the shoulder *B* on the head of the bottle *A* but draw the metal downwardly so that the angle between the top 1 and the flange 2 of the cap assumes more or less the form of a curve 85 (see Fig. 5). The ultimate result is that the caps are more firmly or positively interlocked with bottle-heads when attached in 90 accordance with this invention, so that a lighter grade of stock in the metal of the cap may be used.

It will be understood that the circle in 95 which the axis of movement (approximately the point *C*) of each jaw lies is relatively close to the circle vertically coinciding with the acting portions *y* of the jaws, so that comparatively little movement of each jaw is required in order to cause it to force 100 the cap-flange into interlocking relation with the bottle-shoulder. Also that, because each jaw has a recess 3 receiving what is initially the angle between the top and the flange of the cap, the drawing action above 105 referred to is accentuated and the whole of the outer part of the cap drawn into closer relation with the mouth of the bottle, producing thereby a condition of compression 110 in the lining of the cap which is greater both in degree and in extent of area than it would otherwise be.

The present application is a division of our application Serial No. 447,968, filed 115 August 11, 1908.

Having thus fully described our invention, what we claim and desire to secure by Letters Patent is:

1. The method of closing bottles having locking shoulders near their mouths which 120 consists in superimposing upon a bottle-mouth a cap having a previously corrugated depending flange, and then applying pressure operating directly against the several inner corrugations of the cap-flange and 125 thereby bending the same under the bottle-shoulder, substantially as described.

2. The method of closing bottles having locking shoulders near their mouths which 130 consists in superimposing upon a bottle-

mouth a cap having a previously corrugated depending flange, and then applying a drawing pressure operating directly against the several inner corrugations of the cap-flange 5 and thereby drawing the same under the bottle-shoulder, substantially as described.

3. The method of closing bottles having locking shoulders near their mouths which consists in superimposing upon a bottle-
10 mouth a cap having a corrugated depending flange, and then applying a drawing pressure against the upper part of the cap and

also directly against the several inner corrugations of the cap-flange and thereby drawing the cap-flange under the bottle-shoulder, 15 substantially as described.

In testimony, that we claim the foregoing, we have hereunto set our hands this 17th day of February, 1909.

BENJAMIN ADRIANCE.
AMOS CALLESON.
